UNITED STATES PATENT OFFICE.

CHARLES A. ROBERTSON, OF SPRINGFIELD, ILLINOIS, ASSIGNOR TO MONTGOMERY WARD & CO., INC., OF CHICAGO, ILLINOIS, A CORPORATION OF ILLINOIS.

IGNITION-TIMING MECHANISM.

Application filed November 14, 1921. Serial No. 515,177.

To all whom it may concern:

Be it known that I, CHARLES A. ROBERTSON, a citizen of the United States, residing at Springfield, in the county of Sangamon and State of Illinois, have invented certain new and useful Improvements in Ignition-Timing Mechanism, of which the following is a specification.

This invention relates to control mechanism for internal combustion engines, and has to do particularly with an improved arrangement of means for timing and controlling the ignition incident to operation of the engine.

15 The general purpose of the invention is the provision of an extremely simple mechanism for timing the operation of a magneto, or other energizing source, relative to the operation of an internal combustion engine.

20 An incidental object is the provision of a simple construction for varying the timing of the ignition device within certain limits.

25 Another object is the provision of a simple mechanism for operating a magneto in proper timing with an internal combustion engine.

30 Other and further objects will be pointed out hereinafter, indicated in the appended claims or made obvious from the following description of a particular embodiment of the invention. This embodiment, shown in the drawing forming a part of the specification, is here presented for the purpose of illustration merely, I being aware that the 35 structure is susceptible of modification and variation without departing from the essential features which I regard as constituting my invention.

30 In the drawing—
40 Fig. 1 is a side view of portions of an internal combustion engine, showing certain parts in sectional elevation; and

45 Fig. 2 is a detail showing the arrangement of parts at the extremity of the ignition arm.

50 Referring to these drawings in detail, let it be understood that the numeral 1 designates the cylinder of an internal combustion engine in which the piston 2 operates. The engine shaft 4 carries an inertia wheel 5, and is driven by the piston through the instrumentality of a connecting rod 6. A valve 7 controls exhaust from the cylinder 1. The engine shaft 4 carries a spur gear

8 which drives a timing gear 9 which, inasmuch as the present disclosure is intended to illustrate a four cycle engine, bears a gear ratio to the spur gear 8 of two to one. The timing gear 9 is conjoined to a sleeve 10 which rotates on a post 11 as a bearing. 55 The sleeve 10 carries a timing cam 12 which is effective upon a roller 14 carried on a tappet rod 15 the rear end of which is bifurcated for guidance upon the post 11. The forward extremity of the tappet rod 15 is 60 connected with an ignition arm 16 which is pivoted at 17 and restrained under the influence of spring 18 to maintain the roller 14 in operative contact with the cam 12. The ignition arm 16 constitutes a lever, the 65 upper arm of which terminates in association with the trip lever 19 of an ignition device 20, here illustrated as a magneto of the oscillating type. An electrical conductor 21 forms a path through which energy may 70 be transmitted to a proper ignition plug mounted in the engine cylinder. The magneto is of conventional form, and it will be understood that upon the rocking of the 75 arm 19, which is pivoted at 19^a, the conductor 21 will be energized to produce a spark at the terminals of the plug, this being accomplished at the quick return of the trip lever 19 to normal position under influence 80 of the springs 19^b. As a means for thus 85 swinging the trip lever 19 automatically and in proper time with the operation of the engine, I provide on the upper portion of the ignition arm 16 a pallet 22 which is pivoted at 22^a in a slot in the upper end of the arm. 90 This pallet at its rearward extremity has a nose portion 22^b designed to contact a roller carried on the trip lever 19 of the magneto 20. A spring 24 tends to rock the 95 pallet on its pivot and restrain its nose in raised position. The degree of elevation of the nose of the pallet is controlled by an eccentric member 25 which is rotatably mounted on the arm 16 by a trunnion 26. A manually operable handle 27 extends 100 radially from the trunnion 26 and affords means whereby the eccentric member 25 may be rotated. Incident to operation of the engine, the shaft 4 is rotated, driving timing gear 9 and reciprocating tappet rod 15 105 through the instrumentality of cam 12. This swings ignition arm 16 in proper time with the operation of the engine piston. As the

upper end of the ignition arm swings rearwardly, the nose of the pallet 22 engages the roller at the lower extremity of the trip arm 19, swinging said arm rearwardly 5 against the influence of springs 19^b. When the lower end of trip arm 19 has thus been raised to a suitable elevation, the roller escapes over the nose of the pallet 22 and the lever is returned to normal position, in 10 the course of said movement inducing energization of the conductor 21 and a resulting spark in the ignition plug. The extent to which the arm 19 is swung rearwardly, therefore, depends upon the elevation of the 15 nose of the pallet 22. This, as stated above, is controlled by the adjustment of the eccentric member 25. To retard the spark therefore the eccentric member 25 is adjusted to raise the nose of the pallet, while to advance 20 the spark the eccentric member 25 is adjusted to lower the nose of the pallet, thus permitting an earlier escape of the trip lever from it. Upon a forward movement of the 25 upper end of the arm 16, the pallet escapes under the roller of the trip arm 19, the inclined top face of the pallet riding thereunder and inducing the rocking of the pallet against the influence of its spring 24. The device thus affords a simple mechanism for 30 operation of the magneto by the engine, insuring operation thereof at the proper stroke of the piston, yet permitting a certain variation of the timing of the spark.

I claim:

- 35 1. In an internal combustion engine including an oscillating magneto, the combination of an oscillatory trip lever for actuating the magneto, an oscillatory ignition lever having a free 40 end adjacent the free end of the trip lever, means for oscillating the ignition lever to swing its free end across the free end of the trip lever, and a pallet carried by the free end of the ignition lever for engagement 45 with the trip lever, said pallet being arranged to engage the trip lever on movement in one direction and to escape by the trip lever in movement in the opposite direction.
- 50 2. In an ignition timing mechanism of the class described, the combination with an internal combustion engine, and a magneto having an oscillatory trip arm, of an ignition lever having one of its ends mounted 55 for oscillation with respect to the oscillatory trip arm of said magneto, means for operating said ignition lever, a pallet pivotally mounted in said end of said ignition lever, one of the ends of said pallet constituting a nose for engaging the trip arm of the magneto to actuate said arm in one direction, and means for adjusting the other 60 end of said pallet to vary the contact relation of said nose with the trip arm of the magneto.

magneto, whereby to vary the period of engagement of the pallet and said trip arm. 65

3. In an ignition timing mechanism of the class described, the combination with an internal combustion engine, and a magneto having an oscillatory trip arm, of an ignition lever in substantial axial alignment with the trip arm of the magneto, means for oscillating said ignition lever with respect to said trip arm, a pallet arranged across the contiguous ends of said trip arm and ignition lever and having pivotal connection with the latter to be moved by the ignition lever transversely of the trip arm, one end of said pallet constituting a nose adapted to engage the trip arm to actuate 70 the same in one direction, and means for adjusting the angular relation of the pallet to said ignition lever to vary the period of engagement of said pallet and trip arm. 75

4. In an ignition timing mechanism of the class described, the combination with an internal combustion engine, and a magneto having an oscillatory trip arm, of an ignition lever having one of its ends mounted for oscillation with respect to the oscillatory trip arm of said magneto, means for operating said ignition lever, a pallet pivotally connected across one end of said ignition lever, one of the ends of said pallet constituting a nose for engaging the trip arm of the magneto, means interposed between said end of the pallet and the ignition lever for normally urging the engaging end away from the ignition lever, and an adjusting element cooperating with the other end of the pallet to vary the contact relation of the engaging nose with the trip arm of the magneto, whereby to vary the period of engagement of the pallet and said trip arm. 90

5. In an ignition timing mechanism of the class described, the combination with an internal combustion engine, and a magneto having an oscillatory trip arm, of an ignition lever having one of its ends mounted for oscillation with respect to the oscillatory trip arm of said magneto, means for operating said ignition lever, a pallet pivotally connected across one end of said ignition lever, one of the ends of said pallet constituting a nose for engaging the trip arm of the magneto, means interposed between said end of the pallet and the ignition lever for normally urging the engaging end away from the ignition lever, and an adjusting element carried by the ignition lever and cooperating with the other end of the pallet to vary the contact relation of said nose with the trip arm of the magneto, whereby to vary the period of engagement of the pallet and said trip arm. 105

In testimony whereof I have hereunto signed my name.

CHARLES A. ROBERTSON.
